Jno. F. Rathbone, Albany, A. Y.

Letters Patent/Design No. 54 dated 10th July 1846

The schedule referred to in these Letters Patent
and making part of the same

to all whom it may concern:

Be it known that I, John F. Rathbone, of Albany, in the County of Albany, and State of New York, have invented or produced a new ornamental design for a cooking stove, and I do hereby declare that the following is a full, clear and exact description of the same, reference being had to the accompanying drawings making part of this specification, in which Fig. 1. represents a perspective view of one of my stoves; - Fig. 2. a view of the sides (both sides being alike) upon a larger scale to show the detail of ornament, and Fig. 3. a view of one half the front; - the other half being similar to, and symmetrical with the portion represented. The panel 2, b, which forms the oven door is repeated upon the rear of the stove, which is otherwise plain. - The ornaments consist of four rows of leaves surrounding panels filled with dice-work, foliage, scrolls, &c, not easily described in words but fully represented in the drawings.

What I claim as my invention, and desire to secure by letters Patent is, the combination and arrangement of ornamental figures herein shown and described, forming an ornamental design for a cooking stove.

Witnesses,
Wm. L. Ellison }
